[57] CLAIM

The ornamental design for a gun sight, as shown and described.

DESCRIPTION

FIG. 1 is a perspective view of the gun sight shown as it would be positioned on the top and backside of a gun;

FIG. 2 is a top plan view of the gun sight;

FIG. 3 is a front plan view thereof;

FIG. 4 is a lateral plan view thereof;

FIG. 5 is a rear plan view thereof; and,

FIG. 6 is a bottom plan view thereof.

The broken line showing of a gun in FIG. 1 is for illustrative purposes only and forms no part of the claimed design.
